UNITED STATES PATENT OFFICE.

IRA T. LEE, OF GURDON, ARKANSAS, ASSIGNEE OF ONE-HALF TO O. E. DODGEN, OF GURDON, ARKANSAS.

STORE-GOODS LIFTER.

No. 895,406.

Specification of Letters Patent. Patented Aug. 4, 1908.

Application filed July 22, 1907. Serial No. 384,952.

To all whom it may concern:

Be it known that I, IRA T. LEE, a citizen of the United States, residing at Gurdon, in the county of Clark, State of Arkansas, have invented certain new and useful Improvements in Store-Goods Lifters; and I do hereby declare the following to be a full, clear, and exact description of the invention, such as will enable others skilled in the art to which it appertains to make and use the same.

This invention relates to store goods lifters and has for its object to provide a simple device of this character which shall be efficient in action and easy to operate.

A further object is to provide a device of this character, mounted on a movable truck which shall embody means for removing boxes or similar articles from remote shelves and distributing the same to other shelves or conveying the same to the operator of the device.

A further object is to provide efficient means whereby the device may be controlled by a person standing on the floor or on the truck of the device.

In the accompanying drawings in which like numerals of reference indicate similar parts in the several views, Figure 1 is a side elevation of the device, Fig. 2 is a vertical sectional view through the same, Fig. 3 is a detail vertical longitudinal sectional view through the box removing mechanism, Fig. 4 is a top plan view thereof, and Fig. 5 is a detail sectional view on the line 5—5 of Fig. 2.

Referring to the drawings 6 denotes a truck and 7, the platform thereof. The platform 7 is supported on wheels 8, mounted in bearings 9 on the underside thereof and the said wheels 8 are adapted to run on tracks 10 on the floor of the store or warehouse in which the device is to be used. A running-board 11 is provided near the shelves of the store or warehouse and is adapted to overlie one side of the truck to prevent tilting of the same in one direction and a right-angularly bent bar 12 is secured to each of the bearings 9 on the side opposite to the running-board to engage the underside of the tread of the rail to prevent tilting of the truck in the other direction.

A rectangular opening 13 is provided at the center of the truck platform to receive the lower end of a hollow rectangular shaft 14 which is pivoted on a rod 15 mounted in bearing blocks 16 secured on the underside of

the platform near the sides of the rectangular opening therein.

Telescopically mounted in the shaft 14 is a similar shaft 17, provided on one of its faces with a series of rack teeth 18, said series of teeth extending from the base of said shaft to a point near the top of the same. The front face of the shaft 14, adjacent the rack teeth 18 on the shaft 17, is slotted as at 19 at its upper end to receive a pinion 20 on a shaft 21 mounted in suitable bearings on the shaft 14. Keyed to the shaft 21 near one of its ends is a sprocket gear 22 and a sprocket chain 23 connects said gear with a similar gear 24 disposed beneath the same, on a shaft 25 to the end of which is keyed a pinion 26 adapted to mesh with a gear 27 on a shaft 28 also suitably supported on the shaft 14. A crank handle 28' is secured to the gear 27 and it will be seen that by rotating said gear in one direction the shaft 17 will be elevated and by rotating the same in the opposite direction the said shaft will be lowered.

A rectangular sheet metal plate 29 partially surrounds said shaft 14, is secured thereto, and has its ends 30 extended beyond the front face of the same. The said ends are bent at right angles to form a bearing or guide for rollers 31 mounted on a shaft 32. Secured to the center of said shaft 32 is a staple 33 to which is fastened one end of a lever 34 pivoted as at 35 in a standard 36 on the platform 7. The other end of said lever is provided with a handle 37 and on said lever near said handle is a ring or eye 38, which, when said lever is swung to a substantially vertical position, is adapted to engage a spring latch 39 to hold the said lever in upright position. The latch 39 as here shown consists of a bar 40 pivoted as at 41 in a bearing 42 and has an inwardly projecting right angularly bent portion 43 to seat against the standard to limit the movement of the said bar. A spring 44 is secured to the bearing 42, engages the inner face of the bar 40, and serves to hold the same in its normal position. The standard 36 is securely braced upon the truck platform 7 by means of braces 45.

It will be understood that when the lever 34 is in the position shown in Fig. 2 of the drawings, the shafts 14 and 17 will be in a vertical position, and that when the spring latch 39 is disengaged from the ring or eye 38 and the lever swung to a horizontal posi-

tion the said shaft will be inclined, in the direction of the shelves on which the device is adapted to operate, by means of the rollers moving in the bearings or guides 30.

5 Adjacent the top of the shaft 17 is secured a box removing and depositing mechanism 46. A rectangular plate 47 has an opening near one of its ends through which the upper end of the shaft 17 is adapted to pass. On 10 the upper face of the plate 47 is provided a rectangular frame 48 and said plate has its sides bent to form guide flanges 49. A finger plate 50 comprising a body portion 51 and fingers 52 is adapted to slide on said plate in 15 said flanges and is adapted to be held in extended position by a spring catch 53 seated in the plate 47 and engaging a suitable opening 53^a in the plate 50, and to be retracted, when said catch is disengaged, by means of 20 springs 54 which are secured as at 55 to the rear end of the body portion 51 of the plate 50 and to one of the end rods of the frame 48 as shown at 56. A cord or rope 57 is connected to the catch 53, extends downwardly within reach of the operator of the 25 device, and is adapted to be pulled to disengage the said catch from the plate.

Pivoted mounted on the upper end of the shaft 17 in brackets 58 is a rod 59 having its 30 outer end provided with a hook 60 to engage suitable rings in the boxes or goods to be lifted to remove them from the shelves and hold them in position on the fingers 52. The inner end of the rod 59 is pivotally connected 35 to one end of a rod 61 as at 62 which rod is pivoted near its middle to link 63 which in turn is pivoted to one of the upper end rods of the frame 48. To the other end of the rod 61 is attached a depending cord 64. It will 40 be readily seen that when the cord 64 is pulled downwardly the rods 59 and 61 and the link 63 will assume a position shown by dotted lines in Fig. 3, thereby disengaging the hook 60 from the ring on the box or other 45 article to be moved. A coil spring 65 connected at one end to the pivot 62 and at the other end to a cross bar 66 of the frame 48 serves to return the rods to their normal position. A cord or rope 66 is connected to the 50 body portion of the finger plate 50 as at 67, extends over a guide pulley 68 and the front edge of the plate 47, and hangs within the operator's reach. It being desired to extend the finger plate 50, the same being in its re- 55 tracted position, the cord or rope 66 is pulled downwardly until the catch 53 is in engagement with the aperture 53^a in the finger plate.

When it is desired to remove a box from 60 one shelf and transport it to another shelf and deposit it thereon, the truck is moved to a position opposite the box and the shaft 17 elevated so that the box removing mechanism is in proper position to engage the box. 65 The shafts 16 and 17 are then tilted and the

hook 60 engaged with the ring in the box after which the finger plate is extended under the box and the shaft caused to assume a vertical position. By reversing this procedure the box may be deposited on any desired shelf or may if desired be lowered within reach of the operator for removal.

What I claim as new is:—

1. A device of the character described comprising a truck, an extensible shaft pivotally mounted thereon, a standard on said truck, a lever pivoted on said standard and having rollers on the end thereof adjacent the said shaft, a bearing on said shaft for said rollers, and means on said shaft to engage and support a box or the like.

2. A device of the character described comprising a truck, an extensible shaft mounted thereon, a rame on said shaft, a plate on said frame, means for projecting and retracting said plate, a hooked rod pivoted to said shaft to engage a box or similar article, and means for operating said rod.

3. A device of the character described comprising a truck, an extensible shaft mounted thereon, a frame on said shaft, a finger plate on said frame, springs connected to said frame and said finger plate for retracting the latter, a cord connected to said plate for projecting the same, a spring catch adapted for engagement with said plate to hold the same in extended position, a cord to operate said catch, a rod, a hooked rod pivoted to the upper end of the shaft and to 100 said first-mentioned rod, a link connecting the latter with said frame, a cord connected to said rod to operate the same, and a spring connecting the pivotal point of the two rods with the said frame.

4. A device of the class described comprising a truck, a support mounted for rocking movement upon the truck, a lever pivotally mounted upon the truck, rollers journaled at one end of the lever, a bearing for 110 the rollers carried by said support, and means upon the support to engage and support a box or the like.

5. A device of the class described comprising a truck, a support mounted for rocking movement upon the truck, a lever pivotally mounted upon the truck, rollers journaled at one end of the lever, a bearing for the rollers carried by said support, said bearing being in the form of a collar engaged 120 upon the support and having flanges between which and the said support the rollers are engaged, and means on said support for engaging and supporting a box or the like.

In testimony whereof, I affix my signature, 125 in presence of two witnesses.

IR A T. LEE.
